UNITED STATES PATENT OFFICE.

WILLIAM BIRD DALE, OF CHICAGO, ILLINOIS, ASSIGNOR TO STREET & KENT MFG. COMPANY, OF CHICAGO, ILLINOIS, A CORPORATION OF ILLINOIS.

BASIN FAUCET.

Application filed October 24, 1925. Serial No. 64,513.

This invention relates to a water faucet for wash basins and the like. It is an object of this invention to provide an improved faucet of the class described, wherein both the seat and valve are replaceable and further these parts seat and open without relative twisting, so that wear on the seat and valve due to such twisting is entirely eliminated, thus giving a much longer life to the valve parts before replacement is necessary.

It is a further object of this invention to provide an improved faucet wherein the water passages will be free and unobstructed by the valve closing member when in open position, and wherein the valve operating mechanism will not be exposed to the direct action of water at any time.

Other and further important objects of this invention will be apparent from the disclosures in the specification and the accompanying drawings.

This invention (in a preferred form) is illustrated in the drawings and hereinafter more fully described.

On the drawings:

Figure 1 is a side elevation of a faucet embodying the features of this invention;

Fig. 2 is a front elevation partly in section to show the valve parts; and

Fig. 3 is a section on the line III—III of Fig. 2.

As shown on the drawings:

The faucet body 10 terminates in the usual pipe nipple 11, a delivery nozzle 12 extending outwardly from the body to overhang the basin. As shown in Figure 2, the body is provided with a central vertical partition 13, the water supply passage 14 leading up to the left side of the partition and the delivery passage 15 on the right side thereof leading to the nozzle. The body is provided with an outstanding neck or bonnet 16 for the valve operating mechanism, the neck 45 having a polygonal passage 17 forming an offset from the delivery passage 15.

A plug 18 conforming to the polygonal passage 17 carries a renewable composition valve disc 19 secured to the end thereof in a position to engage a renewable valve seat ring 20 screwed into an aperture in the partition 13, the valve seat ring having slots or lugs 21 in the central passage to engage a screwdriver or other tool for placing and

removing the ring. The plug 18 is centrally threaded for the faucet shaft 22, the outer end of which is engaged by a suitable handle 23. A collar 24 on the shaft is provided to prevent endwise motion thereof, a washer 25 recessed to receive the shaft collar, seating against a shoulder within the neck 16 of the body. A composition washer 26 engages the outer face of the collar and fits over the end of the neck, being clamped thereagainst by a conical packing nut 27 containing an outer sealing washer 28 and packing 29. The composition washer 26 seals the joint between the neck and packing nut, while the packing 29 seals against leakage along the shaft.

The polygonal form of plug is provided to prevent rotation thereof, so that if pitting of the valve seat ring occurs the valve disc will always seat in the same position and will therefore conform to the surface of the valve seat without wearing or tearing the material forming the disc as would be the case if the disc rotated during closure. This feature has been formed to materially lengthen the life of the disc and seat.

I am aware that many changes may be made and numerous details of construction may be varied through a wide range without departing from the principles of this invention and I do not purpose limiting the patent granted hereon, otherwise than necessitated by the prior art.

I claim as my invention:

In a faucet, a body having inlet and outlet passages, a partition therebetween, a valve seat ring removably secured in said partition, a neck on said body forming a polygonal guide passage axially aligned with said seat ring and having an internal shoulder at its outer end, a polygonal plug non-rotatively interfitting in said guide passage, a valve disk carried by said plug, a screw shaft engaging said plug, a rigid collar on said shaft, a washer seating within the shoulder of said neck and having a recessed portion with the neck the recess of which receives said collar, a sealing washer on said shaft outside said collar and seated against the end of the neck, a packing nut adapted to clamp said sealing washer against said neck, and packing within said nut.

In testimony whereof I have hereunto subscribed my name.

WILLIAM BIRD DALE.
